UNITED STATES PATENT OFFICE.

POWELL EVANS, OF PHILADELPHIA, PENNSYLVANIA; ASSIGNOR, BY MESNE ASSIGNMENTS, TO INTERNATIONAL SPRINKLER COMPANY, OF PHILADELPHIA, PENNSYLVANIA, A CORPORATION OF PENNSYLVANIA.

RESERVOIR CONSTRUCTION.

SPECIFICATION forming part of Letters Patent No. 728,691, dated May 19, 1903.

Application filed December 16, 1902. Serial No. 135,407. (No model.)

To all whom it may concern:

Be it known that I, POWELL EVANS, a citizen of the United States, residing in Philadelphia, Pennsylvania, have invented certain 5 Improvements in Reservoir Construction, of which the following is a specification.

My invention relates to certain improvements in tanks for the storage of fluid, and more particularly consists in an improved 10 supporting structure for an elevated tank designed to supply water to any desired type of fire-extinguishing system.

The object of the invention is to provide a strong and reliable supporting structure for 15 a tank of the nature noted above which shall be capable of fulfilling, in addition to its ordinary function, the function of a supplementary reservoir to be used for the storage of water to be used as a gravity suction-feed 20 for a pump, as a source of supply for a fire-pump, or any other desired purpose.

A further object of the invention is to so 25 design the elevated tank for the supply of water to a fire-extinguishing system that its supporting structure shall be of such form as to occupy a minimum of floor-space, this latter structure being, moreover, provided with means whereby the stability of the elevated 30 tank shall in no wise be impaired either by the presence or absence of a body of fluid in the supporting structure or reservoir.

These objects I attain as hereinafter set forth, reference being had to the accompanying drawings, in which—

35 Figure 1 is a side elevation, partly in section, showing the outside appearance as well as the detail construction of a supply-tank and its supporting structure designed according to my invention; and Fig. 2 is a diagrammatic side elevation of a building and its tank structure constructed in accordance with my invention, the tank being illustrated as being designed with a series of reservoir-compartments each connected to the fire-extinguishing system on one of the floors of the 40 building.

In the construction hereinafter described it will be understood that the elevated tank or top portion of the structure shown in Fig.

1 and designated by the letter A is primarily 50 designed to supply water to the sprinklers of a system for extinguishing fires in one or more buildings, and for this reason said tank should be placed at an elevation of at least fifteen feet vertically above the highest sprinkler-head of said system. It will be understood by those skilled in the art that it is also frequently necessary or advisable to provide a reservoir to feed the fire-pump of the system, and in city locations, where space is usually 60 an important consideration, it is of vital importance to place this latter reservoir where it does not occupy valuable room or, if possible, in what would otherwise be waste space. At the same time such a reservoir must be in 65 a convenient situation relatively to the pumps and other apparatus of said system.

It is with the idea of efficiently and cheaply attaining the above objects that I provide a single substantially cylindrical stand-pipe 70 whose top portion serves as the primary supply for the sprinkler system and at the same time utilize the lower portion of the structure necessarily required for the support of said elevated tank as a reservoir for water for 75 pumps or other purposes.

In the above drawings, A represents a substantially cylindrical stand-pipe composed of a series of plate-sections riveted together and so designed as to be self-supporting in the ordinary well-known manner. This structure is preferably provided with side stays a^1 for the reception of bolts a^2 , extending into and permanently embedded in a concrete foundation B. The upper portion of the structure 80 A or tank proper is provided with a conical bottom a^3 , provided with a suitable fitting a^4 for attachment to the pipe a^5 , leading to the sprinkler system, which pipe is usually in a number of sections and provided at any point 85 between the bottom of the tank a^3 and the foundation with an expansion-joint a^6 . A second line of pipe (shown at a^7) serves to convey water to and from the reservoir A², formed by the stand-pipe between the bottom 90 of the elevated tank A' and the foundation B, this serving, as above noted, the double function of support for said tank and of wa-

ter-reservoir. When the cubical contents of the reservoir A^2 and the height required for the tank A' above the highest point in the sprinkling system are known, it will be understood that the diameter of the said reservoir or base portion may be easily calculated, while knowing the required contents of the elevated tank and the diameter of the lower portion of the stand-pipe the vertical height of the tank A' may also be computed. While it will be understood that the presence of water within the lower reservoir A^2 serves to strengthen the same as regards its capacity for supporting the tank A' , the lower structure will naturally be designed with sufficient strength to support the tank A' when this latter is filled, irrespective of whether said lower portion contains water or not. In view of the possibility of a collapse of the lower structure under the pressure of the atmosphere in case a vacuum should be formed therein by the drawing off or leakage of the liquid therein I provide an opening or manhole at the upper end of said lower section, having a cover a^7 held closed from the inside, so that should pressure be exerted thereupon from the outside said cover would act as an automatic valve to open inwardly and prevent the crushing or failure of the structure. Internal and external ladders d and d' , respectively, are provided, these being of the ordinary construction well-known to the art. I also preferably construct the upper portion of the stand-pipe with a manhole a^9 in its side, which serves the same purpose as does that in the lower section, there being, if desired, a manhole a^{10} placed in the top or cover of the stand-pipe, through which access may be had to the interior thereof.

It will be understood that the number of sections into which any stand-pipe may be divided may be indefinitely multiplied without involving further invention beyond the mere duplication of the structure shown in the drawings herewith. For example, the stand-pipe may be constructed, as indicated at A' in Fig. 2, with a series of conical partitions a^2 , by which it is divided into a number of independent compartments or reservoirs. Each of these is provided with a pipe a^8 , leading to any desired point of distribution, being, as in Fig. 2, connected to the sprinkler-system equipment of a building C , it being understood that the various tanks may be filled from suitable branch pipes (not shown) connected, if desired, at convenient points to the various single discharge-pipes shown, though, if considered advisable, a single filling-pipe having outlets at each compartment may be employed for this purpose. In said Fig. 2 the sprinklers of each floor c of the building are supplied from a single reservoir independent

of those for other floors, while, as before, the pipe a^6 , connected to the lowest portion of the reservoir, may be connected to a fire or other pump. Any one or more of said compartments may, if desired, be subjected to air-pressure to accelerate the speed of distribution of water.

I claim as my invention—

1. The combination of a water-tank having a plurality of independent chambers, with a building having a plurality of floors, each provided with an independent fire-extinguishing system, with means whereby each chamber of said tank is connected to the fire-extinguishing system of a floor or floors of said building lying at a level below said chamber, substantially as described. 70

2. The combination of a building and a water-tank, said building having a plurality of independent fire-extinguishing systems, and the tank having a plurality of independent chambers each connected to one of said systems, substantially as described. 80

3. The combination of a water-supply tank, a substantially cylindrical water-tight structure supporting said tank in an elevated position, a conduit leading from said second structure, a second fluid-conductor leading from the bottom of the first structure and extending through said water-tight supporting structure, with means included in that portion of the second conductor between the bottom of the elevated tank and the bottom of the supporting structure whereby changes in the distance between said two points may be permitted without injury to the pipe, substantially as described. 90

4. The combination of a water-supply tank, a substantially cylindrical water-tight structure supporting said tank in an elevated position, a conduit leading from said second structure, a second fluid-conductor leading from the bottom of the first structure, said supporting structure and the elevated tank being formed as a continuous cylinder, substantially as described. 100

5. A cylindrical stand-pipe having within it a series of partitions forming a plurality of elevated reservoirs, an independent pipe-line leading from each reservoir, the lower portion of the stand-pipe being an inclosed water-tight structure, and serving to support the elevated portion thereof, said supporting inclosed portion also having a pipe-line leading from it, substantially as described. 110

In testimony whereof I have signed my name to this specification in the presence of two subscribing witnesses.

POWELL EVANS.
